UNITED STATES PATENT OFFICE.

DAVID R. BOWEN, OF ANSONIA, CONNECTICUT, ASSIGNOR TO THE FARRELL FOUNDRY AND MACHINE COMPANY, OF SAME PLACE.

DESIGN FOR A CALENDERING-MACHINE FRAME.

SPECIFICATION forming part of Design No. 25,254, dated March 17, 1896.

Application filed January 20, 1896. Serial No. 576,251. Term of patent 7 years.

To all whom it may concern:

Be it known that I, DAVID R. BOWEN, a citizen of the United States, residing at Ansonia, in the county of New Haven and State of Connecticut, have invented and produced a new and original Design for Calendering-Machine Frames; and I do declare the following to be a full, clear, and exact description of the same, reference being had to the accompanying drawings, forming a part hereof.

In the drawings, Figure 1 represents a side elevation of one of the end pieces of the frame of a calendering-machine, and Fig. 2 represents an edge view of the same.

The essential feature of the design consists of an inverted-U-shaped upright having a cross-bar near the base, the vertical sides of the opening being substantially parallel, the top being arched, and the outer sides or edges being slightly inclined outward and downward and curved outward near the base.

1 1 denote the vertical portions of the upright or frame having substantially parallel inner edges, 2 2, and inclined outer edges, 3 3. The tops of these portions 1 1 are connected by an arch 4, having substantially concentric upper and lower edges, and near the bottom of the upright is the horizontal cross-bar 5. The outer edges of the frame or upright are curved outward at 6 from a point somewhat above the plane of the bar 5 nearly to the base-line.

Having now described my design, I claim—

The design for a calendering-machine frame substantially as shown and described. 35

In testimony whereof I affix my signature in presence of two witnesses.

DAVID R. BOWEN.

Witnesses:

HORATIO M. BROWN,
NORMAN KNIGHT.
